UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

SHEET COLLECTING, ASSOCIATING, AND FOLDING MACHINE.

1,148,004.

Specification of Letters Patent. Patented July 27, 1915.

Application filed November 1, 1912. Serial No. 729,002.

To all whom it may concern:

Be it known that I, HOWARD M. BARBER, a citizen of the United States, and resident of Stonington, in the county of New London 5 and State of Connecticut, have invented a new and useful Improvement in Sheet Collecting, Associating, and Folding Machines, of which the following is a specification.

The object of this invention is to provide 0 novel and effective means for collecting, associating and folding sheets fed from different sources of supply without the use of turning bars or formers, and without causing the sheets to offset or smut.

5 A further object is to provide novel means whereby a collected and associated group of main and multi-insert sheets may be divided longitudinally of the travel of the sheets into two groups of main and insert 20 sheets, the said two groups then combined and a cover sheet associated therewith and the complete product subjected to stitching and folding operations and finally delivered at a predetermined point.

25 This invention consists more particularly in certain improvements in sheet collecting, associating and folding machines whereby a plurality of sheets may be cut from the main web, collected and then associated with 30 a sheet fed from an extra source of sheet supply such as an insert sheet, the so associated main and extra sheets being slit longitudinally into two groups and the two groups led transversely in opposite directions and then brought together and a sheet 35 from another source of sheet supply, such as a cover sheet, associated therewith, and the so associated sheets subjected to stitching and folding operations.

40 In the accompanying drawings, Figure 1 illustrates in front elevation so much of a sheet associating and folding machine embodying my invention as is necessary to a complete understanding of the relative ar-

45 rangement of the several mechanisms, Fig. 2 illustrates the machine in side elevation, Fig. 3 is a diagrammatic section on an enlarged scale through a portion of the machine which is directed to the collection, association and slitting of the main and multi- 50 insert sheets, Figs. 4 and 5 combined is a diagrammatic section through the portion of the machine which is directed to the combining of the divided groups of main and

insert sheets, the association therewith of 55 the cover sheet and the stitching, folding and delivering of the product, Fig. 6 is a detail section showing the cam mechanism for operating the folding jaws of the female folding cylinder, Figs. 7 and 8 are detail 60 sections showing the cam mechanism for controlling the collection, association and slitting of the main and insert sheets, Fig. 9 is a detail section showing the cam mechanisms for combining the groups of main and 65 insert sheets and the associating therewith of the cover sheet, Fig. 10 is a detail view showing the cam mechanism for controlling the operation of the grippers on the male folding cylinder, Fig. 11 is a detail view 70 showing the cam mechanism for controlling the operation of the tucking blade on the male folding cylinder, Fig. 12 is a detail plan view of the irregular drive for the stitcher mechanism, Fig. 13 is a detail section showing the cam mechanism for controlling the feeding in and transfer of the cover sheet, and Fig. 14 is a detail section 75 on the scale as Figs. 1 and 2, showing the driving connection between certain of 80 the parts.

The main web is denoted by 1 and the two sources of extra sheet supply by 2 and 3. The source 2 is arranged for feeding in 85 multi-insert sheets and the source 3 is arranged for feeding in cover sheets.

The main web is fed to the coacting rotary transverse cutters 4 and 5 by the feed rollers, pulleys and tapes 6, 7, 8, 9, 10. The main sheet transfer cylinder is denoted by 90 11, its two sets of grippers by 12, 13, the shaft by 14. Guides 15, 16, are arranged to direct the sheets from the rotary cutters 4, 5, to the main sheet transfer cylinder 11 and the disks 17 mounted on the shaft 18 serve 95 to direct the advance edges of the sheets into engagement with the grippers 12 and 13 on the said cylinder.

The multi-insert sheet transfer cylinder is denoted by 19, its set of grippers by 20, 100 and its shaft by 21. A sheet stop 22 is arranged to coact with the multi-insert sheet transfer cylinder 19. The sheet collecting cylinder is denoted by 23, its three sets of grippers by 24, 25, 26, and its shaft by 27. 105

The delivery cylinder is denoted by 28, its set of grippers by 29 and its shaft by 30.

The slitter for dividing the collected, as-

sociated, main and multi-insert sheets is denoted by 31 and its shaft by 32, which slitter is arranged to slit the sheets longitudinally on the delivery cylinder 28.

- 5 Spring pressed rollers 33, 34, are arranged to coact with the collecting cylinder 23, spring pressed rollers 35, 36, are arranged to coact with the delivery cylinder 28 and spring pressed rollers 37 are arranged to coact with the transfer cylinder 19, for holding the sheets on their respective cylinders during their passage through this part of the machine.

The table for receiving the two groups of 15 main and insert sheets from the delivery cylinder 28 is denoted by 38. The two groups of sheets are taken from the table 38 in opposite directions in paths transverse to the previous travel of the sheets by the sets of grippers 39 and 40 of the cylinders 41 and 42, the shafts of which cylinders are denoted by 43 and 44. The cover sheet transfer cylinder is denoted by 45, its set of grippers by 46 and its shaft by 47. A sheet stop 48 is 25 arranged to coact with the cylinder 45. The cover sheet is associated with the group of sheets taken off the table by the cylinder 41 and the other group of sheets taken from the table 38 by the cylinder 42 is combined 30 with the first-named group of sheets and cover sheet on the inclined stitcher table, the means for accomplishing this result comprising the cylinder 49, its set of grippers 50 and shaft 51, and a cylinder 52, its 35 set of grippers 53 and shaft 54.

A stitcher mechanism 55 of any well known or approved construction may be used for stitching the associated sheets on the table 56. A sheet stop 57 is provided 40 for the stitcher table.

Sets of spring pressed rollers 58, 59, 60, and 61, are provided for coacting with the cylinders 45, 41, 49 and 52, respectively, for holding the sheets on the said cylinders 45 during the passage of the sheets through this portion of the machine.

The male folding cylinder is denoted by 62, its set of grippers by 63, tucking blade by 64 and shaft by 65. The female folding cylinder is denoted by 66, its set of folding jaws by 67 and its shaft by 68.

The sheet delivery is herein shown as comprising the coacting endless tape carriers 69, 70, the dropper delivery 71 and 55 the endless delivery carrier 72. The tapes 69 pass around the cylinder 66 and the pulleys 73 on the shaft 74. The tapes 70 pass around the pulleys 75 on the shaft 76 and the pulleys 77 on the shaft 78. The sheet 60 dropper mechanism 71 shown herein is of the type shown in United States Letters Patent No. 738778, dated September 15, 1903. The tapes 72 of the endless delivery carrier pass around the pulleys 79 on the 65 shaft 80 and the pulleys 81 on the shaft 82.

Proceeding to describe the driving connection between the several parts: The shaft 83, driven from the press, drives the vertical shaft 84 through the bevel gears 85, 86. The vertical shaft 84 drives the cross shaft 70 87 through the bevel gears 88, 89. The shaft 30 of the delivery cylinder is driven from the shaft 87 through the gears 90, 91, 92, 93. The slitter shaft 32 is driven from the delivery cylinder shaft 30 through the gears 93, 94. The collecting cylinder shaft 75 27 is driven from the delivery cylinder shaft 30 through the gears 93, 95. The insert sheet transfer cylinder shaft 21 is driven from the collecting cylinder shaft 27 through the gears 95, 96. The cam shaft 97 is driven from the shaft 21 through the gears 98, 99. The transfer cylinder shaft 14 is driven from the shaft 27 through the gears 95, 100. The tucking disk shaft 18 is driven from the 85 shaft 14 through the gears 100, 101.

One of the rotary cutters, in the present instance the rotary cutter 5, is driven from the shaft 14 through the gears 100, 102, 103. The cutters 4 and 5 are geared together 90 through the pairs of gears 104, 105, 106, 107. The web feeding mechanism is driven through the train of gears 108, 109, 110, 111, 112, 113, 114.

The cylinder shaft 54 is driven from the 95 main drive shaft 83 through the gears 115, 116. The shaft 44 is driven from the shaft 54 through the gears 117, 118. The shaft 51 is driven from the shaft 54 through the gears 117, 119, and the shaft 43 is driven 100 from the shaft 51 through the gears 119, 120. The cover sheet transfer cylinder shaft 47 is driven from the shaft 43 through the gears 120, 121, and the cam shaft 122 is driven from the shaft 47 through the gears 105 123, 124. The shaft 125 is driven from the shaft 51 through the train of gears 126, 127, 128.

The stitcher drive includes the bevel gears 129, 130, on the shaft 125, which mesh with the bevel gears 131, 132, on stud shafts, which are connected with the stitcher shafts by the elliptic gears 133, 134, and 135, 136, respectively, so that the movement of the stitchers is accelerated during the staple 115 driving and clenching operation, thereby reducing the time required for this operation to a minimum and increasing the time for subsequent operations.

The female folding cylinder shaft 68 is 120 driven from the shaft 54 through the gears 117, 137, 138. The male folding cylinder shaft 65 is driven from the shaft 68 through the gears 138, 139. The cam shaft 140 is driven from the shaft 65 through the gears 125 141, 142. The dropper delivery shaft 143 is driven from the cam shaft 140 through the gears 142, 144, 145.

The shaft 74 of the tape carrier 69 is driven from the shaft 68 through the gears 130 133

138, 146, 147. The shaft 78 of the tape carrier 70 is driven from the shaft 68 through the gears 138, 148.

The delivery carrier 72 is driven step by step from the cam shaft 140 through the pawl and ratchet and crank and pitman connections 149, 150, 151, 152.

The several cam mechanisms are constructed, arranged and operated as follows:

- 10 A fixed cam 153 is arranged to open the sets of grippers 12 and 13 on the main sheet transfer cylinder 11 for receiving the sheets cut from the main web and a fixed cam 154 is arranged to open the said grippers at the 15 proper times for transferring the sheets to the grippers 24, 25 and 26, on the collecting cylinder 23. A fixed cam 155 is arranged in position to successively open the grippers 24, 25, 26, to receive the sheets from the 20 grippers 12 and 13 of the transfer cylinder 11. A movable cam 156, controlled by a cam 157 on the shaft 97 is arranged to open the grippers 24, 25, 26, of the collecting cylinder every one and one-third revolutions of said 25 cylinder for receiving a multi-insert sheet from the grippers 20 of the transfer cylinder 19. A movable cam 158 controlled by a cam 159 on the shaft 97 is arranged to open the grippers 24, 25, 26, of the collecting cylinder 30 inders every one and one-third revolutions of the collecting cylinder for transferring the collected and associated main and multi-insert sheets to the grippers 29 on the delivery cylinder 28. A fixed cam 160 is ar- 35 ranged to open the grippers 29 on the cylinder 28 at the proper time to deliver the separated groups of main and insert sheets onto the table 38 and keep the grippers open to receive the collected and associated main 40 and multi-insert sheets from the collecting cylinder 23.
- The grippers 20 on the multi-insert sheet transfer cylinder 19 are opened every second revolution of said cylinder to receive a 45 multi-insert sheet from the source 2, by the following cam mechanism: A tumbler cam 161 on the shaft of the grippers 20 engages the tumbler pins 162, 163, every second revolution of the cylinder 19 for opening the grippers to receive the sheet and closing the grippers on the advance edge of the sheet. These pins 162, 163, are moved into and out of their operative position by the yoke 164, lever 165 and cam 166. 50 The grippers 20 on the cylinder 19 are opened every second revolution of said cylinder to transfer the multi-insert sheet to one of the grippers 24, 25, 26, on the collecting cylinder 23 by providing a movable cam 55 167 which is brought into and out of operative position by the cam 168 on the shaft 97. The sheet stop 22 for the multi-insert sheets is opened every second revolution of the cylinder 19 to permit the grippers 20 to 60 grasp the advance edge of a sheet, the mechanism for opening said sheet stop including a cam 169 on the shaft 97 and its connections 170, 171, 172.
- The grippers 46 on the cover sheet transfer cylinder 45 are opened every second revolution of said cylinder to receive a cover sheet from the source 3 by the following cam mechanism: A tumbler cam 173 on the shaft of the grippers 46 engages the tumbler pins 174, 175, every second revolution of the cylinder 45 for opening the grippers to receive the sheet and closing the grippers on the advance edge of the sheet. These pins 174, 175, are moved into and out of their operative position by the yoke 176, lever 177, and cam 178 on the shaft 122. These grippers 46 are opened every second revolution of the said cylinder to transfer the cover sheet to the grippers 39 on the cylinder 41 by providing a movable cam 179 which is brought into and out of operative 70 position by the cam 180 on the shaft 122.
- The cover sheet stop 48 is opened every second revolution of the cylinder 45 to permit the grippers 46 to grasp the advance edge of a cover sheet, the mechanism for opening said sheet stop including a cam 181 on the shaft 122 and its connections 182, 183, and 184.
- A fixed cam 185 is arranged to control the opening and closing of the grippers 39 on the cylinder 41 for receiving the cover sheet from the grippers 46 on the cylinder 45. The closing of these grippers 39 on one group of sheets on the table 38 for conveying them away therefrom and the opening of these grippers 39 for transferring them to the grippers 50 of the cylinder 49 together with the cover sheet is accomplished by means of the following cam mechanism: 90 A tumbler cam 186 on the shaft of the grippers 39 engages the fixed tumbler pin 187 for closing the grippers and the fixed tumbler pin 188 for opening the grippers. The grippers 40 on the cylinder 42 are closed 100 upon the other group of sheets on the table 38 to convey them away therefrom and are opened to transfer the group of sheets to the cylinder 52 as follows: A tumbler cam 189 on the shaft of the grippers 40 is ar- 110 ranged to engage a fixed tumbler pin 190 for closing the grippers on the group of sheets and a fixed tumbler pin 191 for opening the grippers to release the sheets. 115 A fixed cam 192 is arranged in position to open the grippers 53 on the cylinder 52 to receive the group of sheets from the cylinder 42. A fixed cam 193 is arranged to open the grippers 53 at the proper time to deliver the group of sheets onto the stitcher table 56 together with the group of sheets delivered 120 to the stitcher table by the cylinder 49. A fixed cam 194 is arranged to open the grippers 50 of the cylinder 49 to receive the group of sheets from the grippers 39 of the 125 130

cylinder 41. A fixed cam 195 is arranged in position to open these grippers 50 at the proper time to deliver the group of sheets onto the stitcher table 56 together with the 5 group of sheets delivered from the cylinder 52.

The sheet stop 57 for the stitcher table 56 is open for transferring the control of the stitched group of sheets to the grippers 63 1) on the male folding cylinder 62 by means of a cam 196 on the shaft 140 and its connections 197, 198.

The grippers 63 of the male folding cylinder 62 are opened to receive the group of 15 stitched sheets from the stitcher table and closed on said group by the following tumbler cam mechanism arranged to operate every second revolution of the cylinder 62: The shaft of the grippers 63 is provided 20 with a tumbler cam 199 which is arranged to engage the tumbler pin 200 for closing the grippers and the tumbler pin 201 for opening the grippers. These pins are thrown into and out of their operative position by 25 the yoke 202, lever 203, and cam 204, on the shaft 140. The grippers 63 are opened to release the advance edge of the group of sheets to permit the folding off of said group when the tumbler cam mechanism is out of 30 operation, by providing an adjustable stationary cam 211 which engages the stud or roller 212 on the arm 213 of the shaft of the grippers 63.

The movement of the floating tucking 35 blade 64 on the cylinder 62 is controlled by the cam 205, lever 206, and its stud or roller 207. The floating movement of the folding jaws 67 on the cylinder 66 is controlled by a cam 208 on the shaft 68. A fixed cam 209 40 is arranged in position to open the folding jaws at the time of the folding operation and a fixed cam 210 is provided for opening the folding jaws to deliver the folded group of sheets or signature between the carriers 45 69, 70, to be transferred by them to the proper delivery mechanism 71.

The operation of the machine is as follows: The main web is fed down between the 50 rotary cutters 4 and 5 where it is cut transversely into sheets which, in the present instance, are double width sheets, the guides 15, 16, directing these sheets successively to the grippers 12, 13, on the transfer cylinder 11. The sheets are transferred successively 55 from the grippers 12, 13, to the successive grippers 24, 25, 26, on the collecting cylinder 23. In the arrangement of the parts herein shown, each of the grippers on the cylinder 23 collects a group of four main sheets. As 60 each set of grippers on the collecting cylinder collects its complement of main sheets, an insert sheet which, in the present instance is a double width insert sheet, is transferred by the grippers 20 on the cylinder 19 to its coacting set of grippers on the collecting 65

cylinder 23. Each associated group of main and insert sheets is then transferred to the delivery cylinder grippers 29. The group of main and insert sheets is then separated longitudinally by the slitter 31 into two 70 groups. These two groups are delivered by the grippers 39 onto the table 38. These two groups of sheets are then moved in opposite directions transverse to the former path of the sheets and they are finally combined on the stitcher table 56 together with a cover sheet, as follows: One group of sheets is taken by the grippers 40 on the cylinder 42 and is transferred therefrom to the grippers 53 on the cylinder 52. The 75 cylinder 52 then delivers this group of sheets onto the stitcher table 56. At the same time, the other group of sheets on the table 38 is taken by the grippers 39 on the cylinder 41 and as these grippers 39 come opposite the grippers 46 on the cylinder 45 a cover sheet is transferred from the grippers 46 to the grippers 39. The group of sheets is then transferred from the grippers 39 on the cylinder 41 to the grippers 50 on 80 the cylinder 49 and this cylinder 49 delivers the group of sheets onto the stitcher table 56 at the same time that the first described group of sheets from the table 38 is being delivered onto the stitcher table. These 85 combined groups of sheets, together with the insert and cover sheets, are then subjected to the stitching operation, while the movement of the sheets is arrested by the stop 57. The stop 57 is then raised and the 90 stitched sheets or signature is taken by the grippers 63 on the cylinder 62 and folded off along the line of stitches by the coaction of the tucking blade 64 on the cylinder 62 with the folding jaws 67 on the cylinder 66. 95 The stitched and folded signature is then transferred by the delivery carriers 69, 70, to the drop delivery mechanism 71 and therefrom onto the delivery carrier 72.

It is evident that changes might be resorted to in the form, construction and arrangement of the several parts without departing from the spirit and scope of my invention; hence I do not wish to limit myself strictly to the structure herein set forth, but 100

What I claim is:—

1. In a machine of the character described, means for cutting sheets from a main web, means for collecting said sheets, means for associating an extra sheet therewith, means for slitting the so collected and associated sheets lengthwise of their travel into a plurality of groups and means for associating an extra sheet with one of said groups after the slitting operation. 110

2. In a machine of the character described, means for cutting sheets from a main web, means for collecting said sheets, means for associating a multi-insert sheet therewith, means for slitting the so collected 120

125

130

- means for associating a multi-insert sheet therewith, means for slitting the so collected and associated sheets lengthwise of their travel into a plurality of groups, means for 5 associating an extra sheet with one of said groups, means for combining said groups, and means for subjecting the combined groups of sheets to a folding operation.
16. In a machine of the character described, means for cutting sheets from a main web, means for collecting said sheets, means for associating a multi-insert sheet therewith, means for slitting the so collected and associated sheets lengthwise of their 10 travel into a plurality of groups, means for associating a cover sheet with one of said groups, means for combining the said groups, and means for subjecting the combined groups of sheets to stitching and folding 70 operations.
17. In a machine of the character described, means for cutting sheets from a main web, means for collecting said sheets, means for associating an extra sheet there- 15 with, means for slitting the so collected and associated sheets lengthwise of their travel into a plurality of groups, means for combining said groups, and means for subjecting the combined groups of sheets to a folding operation. 75
18. In a machine of the character described, means for cutting sheets from a main web, means for collecting said sheets, means for associating a multi-insert sheet therewith, means for slitting the so collected and associated sheets lengthwise of their travel into a plurality of groups, means for combining said groups, and means for subjecting the combined groups of sheets to stitching 20 and folding operations. 80
19. In a machine of the character described, means for cutting sheets from a main web, means for collecting said sheets, means for associating an extra sheet there- 25 with, means for slitting the so collected and associated sheets lengthwise of their travel into a plurality of groups, means for combining said groups, and means for subjecting the combined groups of sheets to stitching 85 and folding operations. 90
20. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, and means for associating an extra sheet with one of said groups. 95
21. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, and means for associating an extra sheet with one of said groups. 100
22. In a machine of the character described, means for cutting sheets from a main web, means for collecting said sheets, means for associating an extra sheet there- 105 with, means for slitting the so collected and associated sheets lengthwise of their travel into a plurality of groups and means for leading said groups off in opposite directions transversely of their previous travel. 110
23. In a machine of the character described, means for cutting sheets from a main web, means for collecting said sheets, means for associating a multi-insert sheet therewith, means for slitting the so collected and associated sheets lengthwise of their travel into a plurality of groups and means for leading said groups off in opposite directions transversely of their previous travel. 115
24. In a machine of the character described, means for cutting sheets from a main web, means for collecting said sheets, means for associating an extra sheet there- 120 with, means for slitting the so collected and associated sheets lengthwise of their travel into a plurality of groups, means for leading said groups off transversely of their previous travel, and means for associating an extra sheet with one of said groups. 125
25. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, and means for associating an extra sheet with one of said groups. 130
26. In a machine of the character described, means for cutting sheets from a main web, means for collecting said sheets, means associating a multi-insert sheet therewith, means for slitting the so collected and associated sheets lengthwise of their travel into a plurality of groups, means for leading said groups off transversely of their previous travel, and means for associating a cover sheet with one of said groups. 135
27. In a machine of the character described, means for cutting sheets from a main web, means for collecting said sheets, means for associating an extra sheet there- 140 with, means for slitting the so collected and

associated sheets lengthwise of their travel into a plurality of groups, means for leading said groups off transversely of their previous travel, means for associating an extra sheet with one of said groups, and means for combining the said groups.

* 28. In a machine of the character described, means for cutting sheets from a main web, means for collecting said sheets.

10 means for associating a multi-insert sheet therewith, means for slitting the so collected and associated sheets lengthwise of their travel into a plurality of groups, means for leading said groups off transversely of their previous travel, means for associating an extra sheet with one of said groups, and means for combining the said groups.

30 groups.

30. In a machine of the character described, means for cutting sheets from a main web, means for collecting said sheets, means for associating an extra sheet therewith, means for slitting the so collected and associated sheets lengthwise of their travel into a plurality of groups, means for leading said groups off transversely of their previous travel, means for associating an extra sheet with one of said groups, means for combining said groups and means for subjecting the combined groups to a stitching operation.

31. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, means for associating an extra sheet with one of said groups, means for combining said groups, and means for subjecting the combined groups to a stitching operation.

32. In a machine of the character described, means for cutting sheets from a main web, means for collecting said sheets, 60 means for associating a multi-insert sheet therewith, means for slitting the so collected and associated sheets lengthwise of their travel into a plurality of groups, means for leading said groups off transversely of their previous travel, means for 65

associating a cover sheet with one of said groups, means for combining the said groups and means for subjecting the combined groups to a stitching operation.

33. In a machine of the character described, means for cutting sheets from a main web, means for collecting said sheets, means for associating an extra sheet therewith, means for slitting the so collected and associated sheets lengthwise of their travel into a plurality of groups, means for leading said groups off transversely of their previous travel, means for associating an extra sheet with one of said groups, means for combining said groups and means for subjecting the combined groups to a folding operation. 70 75 80

34. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, means for associating an extra sheet with one of said groups, means for combining said groups and means for subjecting the combined groups to a folding operation. 95

35. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, means for associating a cover sheet with one of said groups, means for combining the said groups, and means for subjecting the combined groups to a folding operation. 105 105

36. In a machine of the character described, means for cutting sheets from a main web, means for collecting said sheets, means for associating an extra sheet therewith, means for slitting the so collected and associated sheets lengthwise of their travel into a plurality of groups, means for leading said groups off transversely of their previous travel, means for associating an extra sheet with one of said groups, means for combining the said groups, and means for subjecting the combined groups to stitching and folding operations. 110 115 120

37. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, means for 130
125

associating an extra sheet with one of said groups, means for combining the said groups, and means for subjecting the combined groups to stitching and folding operations.

38. In a machine of the character described, means for cutting sheets from a main web, means for collecting said sheets, means for associating a multi-insert sheet therewith, means for slitting the so collected and associated sheets lengthwise of their travel into a plurality of groups, means for leading said groups off transversely of their previous travel, means for associating a cover sheet with one of said groups, means for combining the said groups and means for subjecting the combined groups to stitching and folding operations.

20 39. In a machine of the character described, means for cutting sheets from a main web, a stationary sheet receiving table, means for collecting said sheets, means for associating an extra sheet therewith, means for slitting the so collected and associated sheets lengthwise of their travel, into two groups, and means for depositing them unfolded on said table.

40. In a machine of the character described, means for cutting sheets from a main web, a stationary sheet receiving table, means for collecting said sheets, means for associating a multi-insert sheet therewith, means for slitting the so collected and associated sheets lengthwise of their travel into two groups and means for depositing them unfolded on said table.

41. In a machine of the character described, means for cutting sheets from a main web, a sheet receiving table, means for collecting said sheets, means for associating an extra sheet therewith, means for slitting the so collected and associated sheets lengthwise of their travel into two groups, means for depositing them on said table and means for leading the two groups off in opposite directions transversely of their previous travel.

42. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table and means for leading the two groups off in opposite directions transversely of their previous travel.

60 43. In a machine of the character described, means for cutting sheets from a main web, a sheet receiving table, means for collecting said sheets, means for associating an extra sheet therewith, slitting the so collected and associated sheets lengthwise of

their travel into two groups, means for depositing them on said table and means for leading the two groups off in opposite directions transversely of their previous travel to the same delivery point.

44. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, and means for leading the two groups off in opposite directions transversely of their previous travel to the same delivery point.

45. In a machine of the character described, means for cutting sheets from a main web, a sheet receiving table, means for collecting said sheets, means for associating an extra sheet therewith, means for slitting the so collected and associated sheets lengthwise of their travel into two groups, depositing them on said table, means for leading the two groups off in opposite directions transversely of their previous travel, and means for associating an extra sheet with one of said groups.

46. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel and means for associating an extra sheet with one of said groups.

47. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel and means for associating a cover sheet with one of said groups.

48. In a machine of the character described, means for cutting sheets from a main web, a sheet receiving table, means for collecting said sheets, associating an extra sheet therewith, slitting the so collected and associated sheets lengthwise of their travel into two groups, depositing them on said table, leading the two groups off in opposite directions transversely of their previous travel, associating an extra sheet with one of said groups, and combining the two groups.

49. In a machine of the character described, means for cutting sheets from a

main web, a sheet receiving table, means for collecting said sheets, means for associating a multi-insert sheet therewith, means for slitting the so collected and associated sheets

lengthwise of their travel into two groups, means for depositing them on said table, means for leading the two groups off in opposite directions transversely of their previous travel, means for associating an extra sheet with one of said groups, and means for combining the two groups.

50. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating a cover sheet with one of said groups, and means for combining the two groups.

25 51. In a machine of the character described, means for cutting sheets from a main web, a sheet receiving table, means for collecting said sheets, means for associating an extra sheet therewith, means for slitting
30 the so collected and associated sheets lengthwise of their travel into two groups, means for depositing them on said table, means for leading the two groups off in opposite directions transversely of their previous travel,
35 means for associating an extra sheet with one of said groups, means for combining the two groups and means for subjecting the combined groups to a stitching operation.

52. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating an extra sheet with one of said groups, means for combining the two groups, and means for subjecting the combined groups to a stitching operation.

53. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating a cover sheet with one of said groups, means for

combining the two groups, and means for subjecting the combined groups to a stitching operation.

54. In a machine of the character described, means for cutting sheets from a main web, a sheet receiving table, means for collecting said sheets, means for associating an extra sheet therewith, means for slitting the so collected and associated sheets lengthwise of their travel into two groups, means for depositing them on said table, means for leading the two groups off in opposite directions transversely of their previous travel, means for associating an extra sheet with one of said groups, means for combining the two groups, and means for subjecting the combined groups to a folding operation. 70 75 80

55. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating an extra sheet with one of said groups, means for combining the two groups, and means for subjecting the combined groups to a folding operation. 85 90 95

56. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating a cover sheet with one of said groups, means for combining the two groups, and means for subjecting the combined groups to a folding operation. 100 105 110

57. In a machine of the character described, means for cutting sheets from a main web, a sheet receiving table, means for collecting said sheets, means for associating an extra sheet therewith, means for slitting the so collected and associated sheets lengthwise of their travel into two groups, means for depositing them on said table, means for leading the two groups off in opposite directions, transversely of their previous travel, means for associating an extra sheet with one of said groups, means for combining the two groups and means for subjecting the combined groups to stitching and folding operations. 115 120 125

58. In a machine of the character described, means for cutting sheets from a 130

- main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating an extra sheet with one of said groups, means for combining the two groups, and means for subjecting the combined groups to stitching and folding operations.

59. In a machine of the character described, means for cutting sheets from a main web, a sheet receiving table, means for collecting said sheets, means for associating a multi-insert sheet therewith, means for slitting the so collected and associated sheets lengthwise of their travel into two groups, means for depositing them on said table, means for leading the two groups off in opposite directions transversely of their previous travel, means for associating a cover sheet with one of said groups, means for combining the two groups, and means for subjecting the combined groups to stitching and folding operations.

60. In a machine of the character described, a sheet receiving table, means for depositing thereon two groups of collected and associated unfolded main and insert sheets and means for leading the two groups off the table in their unfolded condition in opposite directions to the same delivery point.

61. In a machine of the character described, a sheet receiving table, means for depositing thereon two groups of collected and associated unfolded main and insert sheets, means for leading the two groups off the table in their unfolded condition in opposite directions to the same delivery point and means for associating an extra sheet with one of said groups.

62. In a machine of the character described, a sheet receiving table, means for depositing thereon two groups of collected and associated unfolded main and insert sheets, means for leading the two groups off the table in their unfolded condition in opposite directions to the same delivery point and means for associating a cover sheet with one of said groups.

63. In a machine of the character described, a sheet receiving table, means for depositing thereon two groups of collected and associated main and insert sheets, means for leading the two groups off the table in opposite directions, means for associating an extra sheet with one of said groups, means for combining the two groups and means for subjecting the combined groups to a stitching operation.

64. In a machine of the character de-

scribed, a sheet receiving table, means for depositing thereon two groups of collected and associated main and insert sheets, means for leading the two groups off the table in opposite directions, means for associating a cover sheet with one of said groups, means for combining the two groups and means for subjecting the combined groups to a stitching operation.

65. In a machine of the character described, a sheet receiving table, means for depositing thereon two groups of collected and associated main and insert sheets, means for leading the two groups off the table in opposite directions, means for associating an extra sheet with one of said groups, means for combining the two groups, and means for subjecting the combined groups to a folding operation.

66. In a machine of the character described, a sheet receiving table, means for depositing thereon two groups of collected and associated main and insert sheets, means for leading the two groups off the table in opposite directions, means for associating a cover sheet with one of said groups, means for combining the two groups, and means for subjecting the combined groups to a folding operation.

67. In a machine of the character described, a sheet receiving table, means for depositing thereon two groups of collected and associated main and insert sheets, means for leading the two groups off the table in opposite directions, means for associating an extra sheet with one of said groups, means for combining the two groups, and means for subjecting the combined groups to stitching and folding operations.

68. In a machine of the character described, a sheet receiving table, means for depositing thereon two groups of collected and associated main and insert sheets, means for leading the two groups off the table in opposite directions, means for associating a cover sheet with one of said groups, means for combining the two groups, and means for subjecting the combined groups to stitching and folding operations.

69. In a machine of the character described, a sheet receiving table, a collecting cylinder arranged to collect a group of main sheets thereon and associate an extra sheet therewith, a delivery cylinder arranged to take the collected and associated group from the collecting cylinder and a slitter arranged to coat with said delivery cylinder to divide the group of sheets on the delivery cylinder into a plurality of groups, said delivery cylinder being arranged to deposit sheets on said table.

70. In a machine of the character described, a sheet receiving table, a collecting cylinder arranged to collect a group of main sheets thereon and associate an insert sheet

therewith, a delivery cylinder arranged to take the collected and associated group from the collecting cylinder and a slitter arranged to coact with said delivery cylinder to divide the group of sheets on the delivery cylinder into a plurality of groups, said delivery cylinder being arranged to deposit sheets on said table.

71. In a machine of the character described, a sheet receiving table, a collecting cylinder arranged to collect a group of main sheets thereon and associate a multi-insert sheet therewith, a delivery cylinder arranged to take the collected and associated group from the collecting cylinder and a slitter arranged to coact with said delivery cylinder to divide the group of sheets on the delivery cylinder into a plurality of groups, said delivery cylinder being arranged to deposit sheets on said table.

72. In a machine of the character described, a sheet receiving table, means for collecting, associating and longitudinally slitting main and insert sheets and depositing them in two groups on said table, a stitching table, means for transferring the two groups transversely in opposite directions from the sheet receiving table and leading them in separate paths to the stitching table to be combined thereon, and subjecting the combined groups to a stitching operation.

73. In a machine of the character described, a sheet receiving table, means for collecting, associating and longitudinally slitting main and insert sheets and depositing them in two groups on said table, a stitching table, means for transferring the two groups transversely in opposite directions from the sheet receiving table and leading them in separate paths to the stitching table to be combined thereon, means for associating an extra sheet with one of said groups on its way from the sheet receiving table to the stitching table and means for subjecting the combined groups to a stitching operation.

74. In a machine of the character described, a sheet receiving table, means for collecting, associating and longitudinally slitting main and insert sheets and depositing them in two groups on said table, a stitching table, means for transferring the two groups transversely in opposite directions from the sheet receiving table and leading them in separate paths to the stitching table to be combined thereon, means for associating a cover sheet with one of said groups on its way from the sheet receiving table to the stitching table and means for subjecting the combined groups to a stitching operation.

75. In a machine of the character described, a sheet receiving table, means for collecting, associating and longitudinally

slitting main and insert sheets and depositing them in two groups on said table, a stitching table, means for transferring the two groups transversely in opposite directions from the sheet receiving table, leading them in separate paths to the stitching table to be combined thereon, subjecting the combined groups to a stitching operation, and means for subjecting the stitched product to a folding operation.

76. In a machine of the character described, a sheet receiving table, means for collecting, associating and longitudinally slitting main and insert sheets and depositing them in two groups on said table, a stitching table, means for transferring the two groups transversely in opposite directions from the sheet receiving table, leading them in separate paths to the stitching table to be combined thereon, means for associating an extra sheet with one of said groups on its way from the sheet receiving table to the stitching table, means for subjecting the combined groups to a stitching operation, and means for subjecting the stitched product to a folding operation.

77. In a machine of the character described, a sheet receiving table, means for collecting, associating and longitudinally slitting main and insert sheets and depositing them in two groups on said table, a stitching table, means for transferring the two groups transversely in opposite directions from the sheet receiving table and leading them in separate paths to the stitching table to be combined thereon, means for associating a cover sheet with one of said groups on its way from the sheet receiving table to the stitching table, means for subjecting the combined groups to a stitching operation, and means for subjecting the stitched product to a folding operation.

78. In a machine of the character described, means for collecting and associating main and insert sheets and slitting them longitudinally of their travel into two groups, means for leading the two groups off in opposite directions transversely of their previous travel and combining the groups and means for stitching the combined groups transversely of their travel.

79. In a machine of the character described, means for collecting and associating main and insert sheets and slitting them longitudinally of their travel into two groups, means for leading the two groups off in opposite directions transversely of their previous travel and combining the groups, and means for folding the combined groups transversely of their travel.

80. In a machine of the character described, means for collecting and associating main and insert sheets and slitting them longitudinally of their travel into two groups, means for leading the two groups

- off in opposite directions transversely of their previous travel, and combining the groups, and means for stitching and folding the combined groups transversely of their travel.
81. In a machine of the character described, means for collecting and associating main and insert sheets and slitting them longitudinally of their travel into two groups, means for leading the two groups off in opposite directions transversely of their previous travel and combining said groups, means for associating an extra sheet with one of said groups and means for stitching said combined groups transversely of their travel.
82. In a machine of the character described, means for collecting and associating main and insert sheets and slitting them longitudinally of their travel into two groups, means for leading the two groups off in opposite directions transversely of their previous travel and combining said groups, means for associating a cover sheet with one of said groups and means for stitching said combined groups transversely of their travel.
83. In a machine of the character described, means for collecting and associating main and insert sheets and slitting them longitudinally of their travel into two groups, means for leading the two groups off in opposite directions transversely of their previous travel and combining said groups, means for associating an extra sheet with one of said groups, and means for folding said combined groups transversely of their travel.
84. In a machine of the character described, means for collecting and associating main and insert sheets and slitting them longitudinally of their travel into two groups, means for leading the two groups off in opposite directions transversely of their previous travel and combining said groups, means for associating a cover sheet with one of said groups, and means for folding said combined groups transversely of their travel.
85. In a machine of the character described, means for collecting and associating main and insert sheets and slitting them longitudinally of their travel into two groups, means for leading the two groups off in opposite directions transversely of their previous travel and combining said groups, means for associating an extra sheet with one of said groups, and means for stitching and folding the combined groups of sheets transversely of their travel.
86. In a machine of the character described, means for collecting and associating main and insert sheets and slitting them longitudinally of their travel into two groups, means for leading the two groups off in opposite directions transversely of their previous travel and combining said groups, means for associating a cover sheet with one of said groups, and means for stitching and folding the combined groups of sheets transversely of their travel.
- In testimony, that I claim the foregoing as my invention, I have signed my name in presence of two witnesses, this thirty first day of October, 1912.

HOWARD M. BARBER.

Witnesses:

F. GEORGE BARRY,
C. S. SUNDGREN.
